UNITED STATES PATENT OFFICE.

CHARLES E. SARGENT, OF CHICAGO, ILLINOIS.

GAS-DRIVEN AIR-COMPRESSOR.

1,136,488.

Specification of Letters Patent. Patented Apr. 20, 1915.

Application filed August 11, 1911. Serial No. 643,538.

To all whom it may concern:

Be it known that I, CHARLES E. SARGENT, a citizen of the United States, residing at Chicago, in the county of Cook and State 5 of Illinois, have invented a new and useful Improvement in Gas-Driven Air-Compressors, of which the following is a specification.

My invention relates to certain new and 10 useful improvements in gas-driven air-compressors, and is fully described and explained in the specification and shown in the accompanying drawings, in which:

Figure 1 is an elevation of my improved 15 device; Fig. 2 is a section on the radial line 2 of Fig. 1; Fig. 3 is an elevation of a portion of the fly-wheel, being that portion particularly shown as Fig. 2; Fig. 4 is an elevation of the cam and adjacent mechanism; 20 Fig. 5 is a horizontal section on the line 5 of Fig. 4; Fig. 6 is a vertical section on the line 6 of Fig. 4, and Fig. 7 is a detailed section through the starting valve.

Referring to the drawings, 8 is the upper 25 portion of a cylinder and 9 is the lower portion, the same being somewhat larger than the upper portion, the two together forming what is commonly known in the art as a differential cylinder.

10 is a piston having a projecting flange 30 11 at its lower end so that the piston divides the space within the cylinder into three parts, in an upper or explosion chamber, an annular chamber and a lower portion having communication with the crank-case.

12 is a crank-case containing fly-wheels 35 connected by a crank-pin after the ordinary practice. One side of the crank-case has a sector-shaped opening 13 adapted to register with a correspondingly-shaped depression 14 in the adjacent fly-wheel, so that, at the time, the space within the fly-wheel is thrown into communication with the atmosphere therethrough. At other times the fly-wheel fits close enough to the wall of the 45 crank-case to make a substantially tight joint.

A port 15 connects the crank-case with 50 the upper portion of the annular chamber controlling the passage of gas therethrough. A compressed air port 17 also opens into the annular chamber, the same being connected to any place where it is desired to store the compressed gas, the passage of gas through

this port being controlled by a valve 18. 19 is an intake-valve and 20 an exhaust-valve opening into the explosion space above the piston.

21 is a valve-operating cam which is 60 adapted to engage successively rollers 22 and 23, the roller 22 being on a rocker-plate 24, the roller 23 on a rocker plate 25. The rocker-plate 24 is connected to the lower end of the valve-stem of the exhaust-valve 65 20, and the rocker-plate 25 has a tip 26 adapted to engage with a tip 27 on the lower end of the valve-stem of the intake-valve 19, the lower end of this valve-stem also being connected by a link 28 with an upward projection on the rocker-plate 24. The exhaust valve stem carries pivoted to it an inertia governor 29 having a tip 30 adapted to engage with a stationary block 31.

It will be evident from the foregoing 75 construction that the rotation of the countershaft with the cam 21 will alternately operate the exhaust and intake rocker-plates 24 and 25, producing successive operation of the corresponding valves. When the engine 80 is running above a certain predetermined speed, a weight 32 on the inertia governor 29, falling by gravity less rapidly than the exhaust valve stem is moved down by its spring, will cause the tip 30 of the 85 inertia governor to engage with the block 31 holding the exhaust-valve open, and the rocker-plate 24 rotating counter-clockwise from the position shown in Fig. 1. This movement will force the lower end of the intake valve stem to the left so that it will not 90 be engaged by the end of the rocker-plate 25 with the result that the intake-valve will not operate. This position is illustrated in Fig. 4.

95 For the purpose of making the engine self-starting, a valve-stem 33 provided with a roller adapted to be engaged by a cam 34 on the countershaft is provided, and carries upon its upper end a hollow cylinder 35 having a shoulder 36. A valve 37 communicates with a compressed air opening 38 and is provided with a valve-stem 39 entering the cylinder 35 and normally pressed downward by a spring 40. The action of this 100 spring is therefore to hold the valve 37 to its seat and to hold the cylinder 35 up with the shoulder 36 against its seat in the engine-frame. At this time the roller on the lower end of the valve-stem 33 is so elevated 110

as not to be engaged by the cam 34. When compressed air is admitted to the compressed air opening 38 it forces the cylinder 35 downward, this cylinder being of larger size than the valve 37. The cam 34 thus comes into action producing periodical openings of the valve 37 with the result that the engine is started. The cam 34 is so arranged as to open the valve during the normal working stroke, intakes occurring during the intermediate stroke. The moment explosions begin the air-valve will not be raised because the explosion pressure will be sufficient to hold the air-valve to its seat and the cylinder 35 will simply be raised by the cam.

I am aware that considerable variation is possible in the details of this construction without departing from the spirit of my invention, and, while I have described the construction in detail in its preferred form, it is my intention to claim all the novelty which is inherent in the construction as broadly as is permitted by the state of the art. The construction has many advantages some of which can be secured by a modified form of construction which will still embody certain of the principles of my invention. Among these advantages are the self-starting feature and the peculiarly novel and simple construction in which it is embodied, the valve-arrangement combined with the governing method shown. When considered as a compressor, this device is exceedingly efficient because of the relatively-large cooling area when compared to the volume of the compression-space in the annular chamber. Furthermore, the same cooling water can be used for both the engine-space and the compressor, the water being admitted around the cooling space and gradually rising about the engine space so as to work when coldest in cooling the air and when warmest in cooling the engine, therefore, working under the most desirable conditions on both parts of the device.

I claim as new and desire to secure by Letters Patent—

1. The combination with a differential cylinder the head of which is of the smaller diameter, and a crank-case secured to the cylinder, of a differential piston having a smaller part fitting within the smaller head

part of the cylinder and a flange fitting the larger part of the cylinder whereby to form within the structure three spaces, to wit, a combustion chamber in the head of the cylinder, an annular chamber in the lower part of the cylinder, and a crank-case chamber, means causing the operation of the combustion chamber as the corresponding chamber of an internal combustion engine independent of the other two chambers, means for admitting gas to the crank-case chamber, a valve controlled communication between the crank-case chamber and the annular chamber, and an exhaust valve leading from the annular chamber, whereby the crank-case operates as the first and the annular chamber as the second chamber of a two stage compressor.

2. The combination with a differential cylinder the head of which is of the smaller diameter, and a crank-case secured to the cylinder, of a differential piston having a smaller part fitting within the smaller head part of the cylinder and a flange fitting the larger part of the cylinder whereby to form within the structure three spaces, to wit, a combustion chamber in the head of the cylinder, an annular chamber in the lower part of the cylinder, and a crank-case chamber, means causing the operation of the combustion chamber as the corresponding chamber of an internal combustion engine independent of the other two chambers, means for admitting gas to the crank-case chamber, a valve controlled communication between the crank case chamber and the annular chamber, an exhaust valve leading from the annular chamber, whereby the crank-case operates as the first and the annular chamber as the second chamber of a two stage compressor, and a water jacket surrounding the annular chamber and the combustion chamber, and provided with a water intake adjacent to the annular chamber, a water exit adjacent to the combustion chamber, whereby the cooler water surrounds the annular and the warmer water the combustion chamber.

In testimony whereof I have hereunto set my hand.

CHARLES E. SARGENT.

In the presence of—

A. U. THORIEN,
R. A. SCHAEFER.
